ELECTRIC-LIGHTING SWITCH

John I. Reid, York, Pa.

Application July 30, 1946, Serial No. 687,197

2 Claims. (Cl. 200—156)

1

My invention relates to an electric switch for light circuits which is neat in appearance, of simple construction and accordingly is of low cost in manufacturing.

It is a single button switch suitable for houses and buildings of all kinds, in the walls of which it can be inserted so as to be practically invisible.

One embodiment of the invention is illustrated in the drawing in which like numerals refer to the same details in the different views.

Figure 1 is a vertical section of the switch taken at right angles to a wall in which the switch button is located;

Figure 2 is a transverse section on a plane along line 2—2 of Figure 1;

Figure 3 is a face view of a stationary or backing disk to which the positive and negative conductors are directly connected.

All the working parts of the switch are enclosed in the housing 10 which may be made of thin metal-plate or plastic.

This housing 10 is provided with a face plate 11 which is flush with the building wall 12 fastened by wood screws where the switch button 13 is located. This button 13 fits slidably in a tubular neck 14 which forms an extension from the housing 10 and in which a shoulder 15 is provided engaging the button collar 16 for retaining the push button 13 in place flush with the face plate 11 as pushed outwardly by the main spring 17. The latter abuts with its inner end against a shelf 18 in the casing 10.

At 19 in the button 13 is pivoted in pendulum manner, an actuating rod 20 for the switch, an opening 21 being provided in the shelf 18 permitting wide oscillations of the rod 20 for operating the switch. The rod 20 has a sideways directed foot portion 22 the use of which will be described later.

The switch proper consists of a pair of disks 23, 24. The disk 24 is of insulating material and the two disks are mounted close together, one in front of the other, see Figure 2. Disk 24 is circular and attached to the side wall of the casing 10. On the face of disk 24 are provided two short, segmental contact plates 25, 26 of copper or other conductive material in diametrically opposite position and slightly raised above the disk surface. These plates have wire connections with a source of electric current; that is plate 25 with the negative pole and 26 with the positive pole for instance. These contact plates form arcs of a circle in which insulator segments 27, 28 are also located.

The second switch disk 23 is of current con-

ducting material and is of square contour with projecting teeth 29 of non-conducting material at each corner located in the path of the foot 22 on the actuating rod 20. The disks 23, 24 are placed close together on the same axial spindle 30 which is secured in the side wall of the casing 10 and projects beyond the two disks and at its free end carries a compression spring 31 held down by a nut 32. On its surface adjacent to the fixed disk 24 the revolving disk 23 has metallic segments 33, alternating with insulating segments 35, 36 corresponding to the segments 25, 26 and 27, 28 respectively on the same radius on the fixed disk 24, and which are so arranged that current will pass between the two disks in one position of the revolving disk 23 and between the segments 33 and 34, while the line is broken in another position.

At each corner of the square revolving disk 23 is formed a lug or tooth of insulation material 38 which is integral therewith and flat faced and pointed. The relative location of a tooth 29 and the presser foot 22, with the parts in idle position, is such that the foot 22 abuts against a tooth 29 at a point slightly above the center line, Figure 1, it being assumed that the disk revolves counterclockwise as indicated by arrow Y. In this position no current is passing because the insulating segments 35, 36 contact with the insulating segments 27, 28, the disks being pressed together by the coiled spring 31 at the end of the spindle 30.

If now the button 13 is depressed in its bearing 14, against the main spring 17, the actuating rod 20, pivoted at 19 in the button will swing upward, as shown in dot-and-dash lines, as guided by the nearest tooth 29, which is slightly off center. Continued pressure on the button will thereupon swing disk 23 a quarter turn so that the metal segments 33, 34 register with the metal segments 25, 26 on the fixed disk 24 thereby making electric connection. Upon then releasing the button, the disk 23 will remain in set position, held by spring 31 until the button is again depressed, thereby turning disk 23 another quarter turn and opening the circuit. Thus alternately and step by step, current will be switched on and off.

The diameter of the main spring has to be large enough to permit the full swing of the pendulum rod 20 during operation.

It is to be understood that the invention as herein disclosed may be varied from the details described and shown without departure from the spirit of the subjoined claims.

I claim:

1. An electric circuit switch, comprising a housing, a pin secured at one end to a wall of the housing to extend into the center thereof, a pair of disks supported in juxtaposition on said pin, one disk being circular and secured to the pin against rotation, said one disk being of insulation material, the other disk being of polygonal peripheral outline whereby are provided a series of corners, a lug projecting outwardly from each of said corners, said other disk being rotatable on the pin, a spring means encircling the pin between said other disk and the other end of the pin and connected to the said other end of the pin to yieldingly press the disks together, corresponding electric current conducting and non-conducting segments on adjacent surfaces of said disks for alternate connection upon rotation of the said other disk, and an actuating means for the rotatable disk supported for reciprocation toward and successive engagement with said lugs.

2. An electric circuit switch of the character stated in claim 1, in which said actuating means comprises a button supported for reciprocation

5 toward and away from the peripheries of the disk and having its axial center substantially in line with said pin but perpendicular to the length thereof, a rod pivotally attached at one end to the inner end of the button at the longitudinal center of the latter and extending toward the periphery of the rotatable disk and terminating in a laterally directed foot portion for engagement with said lugs, and spring means urging outward movement of the button away from the disks.

JOHN I. REID.
